Cedar Rapids, Iowa

Application August 16, 1935, Serial No. 36,528

3 Claims. (Cl. 230—259)

This invention relates to fans and has particular relation to a motor driven device for moving large volumes of air for cooling purposes.

In the art of conditioning air within a closed space to make it more pleasant for the occupants under conditions of high temperature, it is often the practice to employ devices such as the well known electric fan for circulating air to thus increase the rate of evaporation from the skin thereby tending to decrease the body temperature. Such devices are usually in the form of motor driven fans, the fan diameter being relatively small and the device securing circulation of the air by rotating the fan at high speed thus producing an air current of a relatively small cross sectional area traveling at relatively high velocities.

We have discovered that much better results are secured if a fan of relatively large dimensions is used and the fan rotated at slow speed to provide a more gentle movement of air currents of large volume.

We have found the two bladed propellers usually used for propelling heavier-than-air aircraft particularly suitable for this purpose, and we have devised a strong, simple, reliable, inexpensive and practically frictionless means for supporting and driving fans of this character.

It is accordingly an object of our invention to provide a fan of relatively large dimensions and means for rotatably supporting and driving the fan.

Another object of our invention is to provide a particularly simple and effective supporting structure for a fan.

Other and further features and objects of our invention will be more apparent to those skilled in the art upon a consideration of the accompanying drawing and following specification, wherein is disclosed several exemplary embodiments of the invention, with the understanding, however, that such changes may be made therein as fall within the scope of the appended claims without departing from the spirit of the invention.

In said drawing:

Figure 1 is a view in side elevation of a fan and fan supporting and driving means considered according to one embodiment of our invention.

Figure 2 is a bottom view of the case or housing for supporting the driving mechanism of the device shown in Figure 1, and

Figure 3 is an enlarged sectional view of the device shown in Figure 1 and illustrating the parts of the device.

Referring now to the drawing, we preferably

provide a cupped or recessed case or base 10 for supporting the driving and supporting mechanism and this base is provided with suitable lugs 11 about its periphery to permit the case to be secured to a suitable plate 12 or the like, as illustrated in Figure 1, which plate is in turn secured to the ceiling 13 of a room. The lugs 11 may be secured to the plate 12 by any desired means as, for instance, the lag screws 14 which pass through suitable openings 15 in the lugs 11.

The case 10 is cupped or recessed, as indicated at 17, in order that a large driven pulley 18 and a small drive pulley 19 may be received within the case. A relatively small drive motor 21 is employed and this drive motor is preferably of the so-called vertical type and has a circular flange 23 at the upper end thereof. The circular flange 23 is provided with a pair of rails 22 adapted to engage the under side of the case 10 to permit mounting the motor 21 on the under side of the case, and the armature shaft 24 of the motor projects through a suitable enlarged opening 26 in the case. The case is of relatively small cross sectional dimensions at this point because of the small diameter of the drive pulley 19.

The case 10 is considerably enlarged at its other end in order that the large driven pulley 18 may be received within the case. The case is provided with a large circular opening 31 in the lower wall thereof and this opening 31 is adapted to receive a flanged portion 32a of a collar 32. The collar has a horizontally extending flange 32b and the flange 32b has openings therethrough in order that it may be secured, as by means of bolts 33, to the under side of the case 10. The collar 32a is recessed, as indicated at 34, to receive the stationary race of an anti-friction bearing 36. The rotating race of the bearing 36 is adapted to receive a shaft 37 upon which the large pulley 18 is mounted, the pulley being keyed to the shaft 37 by means of the key 35.

A downwardly extending portion 32c of the collar 32 is adapted to receive the upper end of a pipe 38. The lower end of the pipe 38 is provided with threads 39 on the outer face thereof for receiving a cap 41. This cap is of sufficient diameter at the lower inside wall thereof that the stationary race of anti-friction bearing 43 may be wedged between the inner wall of the cap and the end of the pipe or tube 38. The rotating race 45 of the anti-friction bearing 43 is fitted with a forced fit to an enlarged portion 37a of the shaft 37 and the upper end of the enlarged portion 37a is threaded on the outside wall thereof, as indicated at 37b, in order that a nut 44 may be

threaded thereon. This nut bears against the rotating race of anti-friction bearing 43 and thus prevents the shaft 37 from dropping out of the casing 38. The lower end of the enlarged portion 37a has a circular flange 46 to form a hub. The rotating race is thus clamped between the hub 46 and the nut 44. A packing gland 47 of usual construction is employed at the lower portion of the cup 41 to prevent the seepage of oil downwardly along the shaft and through the cup.

10 The lower end of the shaft 37 is provided with a circular hub 51, which hub is keyed to the shaft by means of the key 52, the hub 51 being held in place against longitudinal movement on the shaft by means of the nut 53. A propeller 54 is mounted on the hub 51, the shaft opening 56 of the propeller being of sufficient diameter that the hub 51 may be received thereon. A hub cap 57 is provided on the outer or lower face of the propeller and the cap 57 and hub 51 are tightly locked on the propeller by means of bolts 58.

15 The large pulley 18 is driven from the small pulley 19 by means of a belt 59. On energization of the motor 21, the shaft 37 is rotated at relatively low speed to rotate the propeller 54, but this speed is sufficient to move a very large volume of air and it has been found that this large volume of slowly moving air is more efficacious in producing a cool sensation than is a small diameter air blast of high velocity. A motor of relatively low power may be used for driving the propeller 54, yet a large volume of air is moved by the propeller. The device is extremely simple in structure and reliable in operation.

20 35 It is apparent that modifications may be made by those skilled in the art and such modifications may be made without departing from the spirit and scope of my invention as set forth in the appended claims.

40 40 We claim as our invention:

1. A fan comprising a case, means for securing the case to the ceiling, a motor, means for mounting the motor on the lower face of the case with the drive shaft thereof projecting through and into the case, a drive pulley on the drive shaft, the case having another opening therethrough, a collar in the opening and depending therefrom, a bearing in the collar, a tube disposed in the collar and projecting therebelow,

a cap on the lower end of the tube, a bearing in the cap, a shaft rotatably mounted in the bearings and projecting upwardly through the last named opening in the case and through the cap, a hub on the projecting end of the shaft, a propeller on the hub, a driven pulley on the upper end of the shaft within the case, and belt means from the drive to the driven pulley.

2. A fan comprising a case having openings therein, a motor, means for mounting the motor on the lower face of the case with the drive shaft thereof projecting through and into the case, a drive pulley on the drive shaft, a collar in another opening in the case and depending therefrom, a bearing in the collar, a tube disposed in the collar and projecting therebelow, a cap on the lower end of the tube, a bearing in the cap, a shaft varying in diameter rotatably mounted in the bearings and projecting upwardly through the openings in the case, a locking means on the shaft at the lower bearing for holding the shaft in a stable vertical position, a hub mounted on the lower end of the shaft, a propeller on the hub, a driven pulley in the upper end of the shaft, and a belt means from the driving to the driven pulley.

3. In a fan, a case having openings therein, a motor and driving means mounted on the case adjacent one opening and extending therethrough, a collar in another opening and depending therefrom, a bearing mounted in the collar, a tube disposed in the collar and extending therebelow, a retaining cap on the lower end of the tube, a bearing mounted in the retaining cap, a shaft extending into the case mounted for rotation in the bearings and having an enlarged partially threaded portion for mounting in the lower bearing, a flange on the lower part of the enlarged portion of the shaft, a locking nut on the threaded part of the enlarged portion of the shaft so that the lower bearing may be locked between the nut and the flange to hold the shaft in a stable vertical position, a hub mounted on the lower end of the shaft, a propeller on the hub, a pulley on the upper end of the shaft, and a belt connecting the driving means and said pulley.
